UNITED STATES PATENT OFFICE.

GEORGE E. DARROW AND GROVER C. TUDDER, OF EUGENE, OREGON.

EXTENSION STEP-LADDER.

1,172,440.

Specification of Letters Patent.

Patented Feb. 22, 1916.

Application filed May 14, 1914. Serial No. 838,421.

To all whom it may concern:

Be it known that we, GEORGE E. DARROW and GROVER C. TUDDER, citizens of the United States of America, residing at Eugene, in the county of Lane and State of Oregon, have invented certain new and useful Improvements in Extension Step-Ladders, of which the following is a specification.

10 This invention relates to new and useful improvements in step ladders and more particularly to an extension step ladder and the primary object of the invention is to provide a ladder which, in its normal position, is reasonably small, but which may be quickly and readily adjusted to various greater heights.

15 A further object of the invention is to provide a ladder formed of two sections adjustable longitudinally with respect to one another and which in the normal position of the device fit one within the other to form one complete ladder.

20 Still another object resides in providing steps or rungs on each section of the ladder, which steps or rungs are adapted to aline in the normal position of the device to form complete step sections for the ladder.

25 A still further object resides in providing interlocking sliding means between the sections of the ladder.

30 A further object resides in providing a device which is simple and durable in construction, inexpensive to manufacture and one which will be very efficient and useful in operation.

35 With these and other objects in view, our invention consists in the novel features of construction, combination and arrangement 40 of parts as will be hereinafter referred to and more particularly pointed out in the specification and claims.

45 In the accompanying drawings, forming a part of this application: Figure 1 is a perspective view of a device constructed in accordance with our invention. Fig. 2 is a side elevation thereof in its extended position; and Fig. 3 is an enlarged horizontal section through one leg of the device.

50 In describing the invention we shall refer to the drawing in which similar reference characters designate corresponding parts throughout the several views and in which—

55 L designates a ladder of the general folding type consisting of side bars B, steps S and a hinged support or prop K.

The invention primarily contemplates the provision of an extensible construction and to this end substantially stationary and movable sections are provided.

60 The side bars B each consist of the spaced apart rails 1 and 2 which are properly braced together at their lower ends by means of the intermediate block or the like 3. The upper ends of the rails 1 and 2 are braced 65 by means of the bracing clamps 4, the latter also forming stops for the movable section, as will appear presently. Slidably mounted between the rails of each bar B is an additional rail 5, the latter having a V-shaped 70 rib or the like, 6, along the edges thereof which are snugly received in similarly shaped grooves or channels 7 in the opposed inner edges of rails 1 and 2.

75 The steps S each consist of a pair of spaced apart sections or rails, one section being carried rigidly between each pair of side rails and rigidly carried at regular intervals between the rails 5 are the additional sections 9 which are adapted to fit between 80 the spaced sections and complete the step sections S. The sections 8, however, are steps or rungs for the lower or stationary portion of the device, while the sections 9 form the same for the movable portion of the 85 device. In the lowermost position of the movable section of the device, the lower ends of rails will abut the blocks 3 and in such position the sections 8 and 9 will properly aline with one another to complete the formation of the steps S.

90 Mounted on the upper ends of the rails 1 and 2 is the top step or support 10 to which is hingedly engaged the support or prop K. This latter consists of the legs or rails 11 95 which are directly hinged to the member 10 and the additional legs or rails 12 to which the rails or legs 11 are adjustably connected. The legs or rails 11 are braced together as at 13 and the lower ends of the legs or rails 11 are provided with guide keepers 14 which 100 slidably receive the legs 12 therethrough. The legs 12 with the rails 1 and 2 and the step sections 8 form what may be termed the lower or stationary portion of the extensible 105 ladder while the remaining parts may be said to be the movable section thereof.

110 It is apparent from the construction as above described that the ladder may be extended, at will, by merely forcing the movable section of the device upwardly with respect to the stationary section and in order

to retain the device in any adjusted position, the friction clamps 15 are provided for the lower ends of the rails 5. These clamps engage the rails 1 and 2 and when 5 properly adjusted, cause said rails to bind tightly against the rails 5, thereby securing the latter in any adjusted position. Additional friction clamps 16 are carried on the upper ends of the legs or rails 12 for binding engagement with the rails or legs 11, whereby to also secure the latter in various 10 adjusted positions with respect to the former. The clamps 16, it will be seen, are carried on the stationary portion of the 15 device, while the clamps 15 are carried on the movable section thereof and the latter clamps are adapted to abut the clamps 4 whereby the outward or upward movement 20 of the movable section is thus limited.

20 It must be here stated that the ladder described above may be constructed of wood, metal or a combination of both and may be of any size and dimension desired.

From the above description of the construction of our improved device, the operation thereof will be readily understood and it will be seen that we have provided a simple, inexpensive and efficient means for carrying out the objects of the invention.

30 While we have particularly described the elements best adapted to perform the functions set forth, it is obvious that various changes in form, proportion and in the minor details of construction may be resorted to, without departing from the spirit or sacrificing any of the principles of the 35 invention.

Having now described our invention what we believe to be new and desire to secure 40 by Letters Patent, is:—

1. In a ladder of the class described, a section including side rails, each composed of a pair of spaced apart parallel bars and steps therebetween each comprising a pair 45 of spaced apart step sections, the inner opposed edges of the bars forming the side rails being provided with V-shaped grooves extending for the greater portion of the length thereof, and an additional section 50 including a pair of side rails disposed between the bars forming the aforesaid side rails, the last mentioned rails being each provided with V-shaped ribs to form wedges whereby to fit snugly in the

aforesaid grooves of said bars, additional 55 step sections carried between the last mentioned side rails adapted to aline with the aforesaid step sections when the additional section is in its lowermost position with respect to the first mentioned section, and means 60 carried by the lower portions of said second mentioned side rails and engaged with the bars of the first mentioned side rails whereby to cause the V-shaped wedges of the second mentioned side rails to frictionally bind 65 within the V-shaped grooves of the first mentioned side rails and permit the movable section to be retained in any adjusted position with respect to the stationary section of the ladder. 70

2. In the ladder of the class described a section including side rails, each composed of a pair of spaced apart parallel bars and steps therebetween, each comprising a pair of spaced apart step sections, the inner opposed edges of the bars forming the side rails being provided with V-shaped grooves terminating at their outer edges in reduced flat portions, said grooves extending for the greater portion of the length thereof, an 80 additional section including a pair of side rails disposed between the bars forming the aforesaid side rails, the last mentioned rails being each provided with V-shaped ribs to form wedges, whereby to fit snugly in the 85 aforesaid grooves of said bars, said V-shaped wedges also terminating at their side edges in reduced flat portions adapted to abut the flat portions of the aforesaid side rails, additional step sections carried by the last 90 mentioned side rails adapted to aline with the aforesaid side sections when the additional section is in its lowermost position and means whereby the lower portions of said last mentioned side rails are engaged 95 with the bars of the first mentioned side rails, whereby to cause the V-shaped wedges to frictionally bind within the V-shaped grooves and permit the movable section to be retained in any adjusted position with respect to the stationary section. 100

In testimony whereof we affix our signatures in presence of two witnesses.

GEORGE E. DARROW.
GROVER C. TUDDER.
